S. A. XIPPAS

FAN BLADE AND CENTER

Filed July 24, 1925

Socrates A. Xippas, Inventor.

By *Walter B. Burrow*
Attorney

UNITED STATES PATENT OFFICE.

SOCRATES A. XIPPAS, OF PITTSBURGH, PENNSYLVANIA.

FAN BLADE AND CENTER.

Application filed July 24, 1925. Serial No. 45,902.

My invention relates to fan blades and centers.

The object of the invention is to provide a center carrier or support for double curved 5 blades or impellers for electric fans particularly those adapted to be used with a vertical motor.

Further objects and advantages will be more fully described herein and specifically 10 pointed out in the claims hereunto annexed recourse being had to the accompanying drawing forming a part of this specification in which:—

Figure 1 is a plan of the completed fan 15 blade center or cross member showing the curved arms thereon.

Figure 2 is a side view of the center or spider.

Figure 3 is an elevation of the fan blades 20 showing their general arrangement.

Figure 4 is a vertical section of one of the fan blades showing the up and down curved form of the same.

Figure 5 is a cross section of one of the 25 blades or impellers showing the curve thereof which is at right angles to that shown in Figure 4.

Figure 6 is a perspective view of a single 30 arm of the center.

Figure 7 is a top plan view of the various 35 blades in their respective positions when mounted upon the carrier shown in Figure 1, and

Figure 8 is a side elevational view of the 40 blade assembly shown in Figure 7.

In the drawing like reference numerals 45 indicate similar parts in all the several views:—

Referring to the drawing, 1 designates a 50 disc forming the center or body of my improved blade support or carrier. This body 1 has outwardly extending equally spaced curved arms 2, each of which consists of a horizontal portion 3, provided at one of its longitudinal extremities with a curved wing 4, bent at an angle to the part 3, so that the 55 arm forms a projection which is substantially L-shaped in cross section.

A pair of the diametrically opposite arms 50, 2, have the wings 4 extending upwardly, while the other pair of arms has the wings 55 extending downwardly. Each wing is of slightly less length than the arm 2, with which it is associated, so that gaps 5 are located between the inner ends of the arms.

The body 1 is perforated at 6. to receive

the upper end of the vertical shaft 14, on which the fan is mounted, and the dotted line 7, indicates the aperture of the disc, while the dotted line 8, represents a circle, 60 at which the inner ends of the wings 4, terminate.

The fan blades are indicated at 9 and 10, and each blade is of the same configuration as each other blade. Each blade is curved 65 up and down as shown at 11, and laterally, as indicated at 12. The blades are secured to the arms 2, by means of screws or rivets which pass through apertures 10^a of the wings of the arms, and the curvature 12 70 of each blade conforms to the lengthwise curvature of the wing to which it is attached.

From Figs. 2 and 3, it may be seen that the downwardly extending wings of diametrically opposite arms 2, diverge downwardly, as indicated at 13, and the wings of the other pair of diametrically opposite arms diverge upwardly in a similar manner. As the blades are curved in the direction of their height, and are secured to the diverging wings 4, it will be understood that the upwardly extending blades 9, diverge upwardly, while the downwardly extending blades 10, diverge downwardly. Owing to this construction, the blades 9, when the 80 shaft 14 is rotated counter clockwise see Figure 1, will draw air downwardly, while the blade 10 will draw air upwardly, and this air is forced outwardly in a horizontal plane away from the shaft 14. 90

The blades, when mounted for operation, are usually confined by a spherical guard, (not shown) having perforations to permit the passage of the air. In view of this fact, the extreme edges of the various blades are 95 shaped to coincide with an imaginary sphere which is concentric with such a guard and, of course, of less diameter.

From the foregoing, it is believed that the construction, operation, and advantages 100 of the invention may be clearly understood, and it is obvious that changes may be made in the details disclosed, without departing from the spirit of the invention, as expressed in the claims.

I claim:

1. In a fan, a blade carrier comprising a central body portion provided with outwardly extending arms, one of said arms being provided along one of its longitudinal extremities with an upwardly extending wing 110 of substantially the same length as the arm,

and another one of said arms being provided along one of its longitudinal extremities with a downwardly extending wing of substantially the same length as the last mentioned arm.

2. In a fan, a blade support comprising a central body portion adapted to be mounted on a fan shaft, curved arms carried by, and extending outwardly from the body portion in a substantially horizontal plane, one of said arms being provided along one of its longitudinal extremities with a curved upwardly extending wing, and another one of said arms being provided along one of its longitudinal extremities with a downwardly extending curved wing.

3. In a fan, a blade support comprising a central body portion adapted to be mounted on a fan shaft, arms radiating from the body portion at angles to the axis of rotation, said arms being arranged in pairs, each arm on one pair being provided along one of its longitudinal extremities with an upwardly extending wing adapted to bear against a fan blade, each arm of the other pair being provided along one of its longitudinal extremities with a downwardly extending wing adapted to bear against a fan blade.

4. In a fan, a blade holder comprising a central body portion adapted to be mounted on a fan shaft, pairs of radiating arms carried by the body portion and arranged at angles to the axis of rotation, each arm of one pair being provided along one of its longitudinal extremities with an extending wing, each arm of the other pair being provided along one of its longitudinal extremities with an oppositely extending wing.

5. In a fan, a blade support comprising a central body portion adapted to be mounted on a vertical shaft, radiating arms carried by the body portion and arranged in pairs, each arm of one pair being provided along one of its longitudinal extremities with an upwardly extending wing, and each arm of the other pair being provided along one of its longitudinal extremities with a downwardly extending wing, the upwardly extending wings diverging upwardly from a horizontal plane drawn through the axis of rotation, and the downwardly extending wings diverging downwardly from another horizontal plane drawn through the axis of rotation.

6. In a fan, a vertical shaft, a blade support, mounted on the shaft and comprising a central body portion, and radiating arms arranged in pairs, each arm of one pair being provided along one of its longitudinal

extremities with an upwardly extending wing, each arm of the other pair being provided along one of its longitudinal extremities with a downwardly extending wing, the upwardly extending wings diverging upwardly from a horizontal plane extending through the shaft, and the downwardly extending wings diverging downwardly from a horizontal plane extending through the shaft and arranged at an angle to the last mentioned plane.

7. A fan, including a shaft, a blade holder mounted on the shaft, and including radiating arms provided with upwardly and downwardly extending wings, upwardly and downwardly extending blades carried by the arms and bearing against said wings, each of said blades being curved in the direction of its height and in the direction of its width.

8. A fan, including a shaft, a blade diverging from a plane drawn through the axis of rotation of the shaft, a second blade diverging from a plane drawn through the axis of rotation of the shaft and at an angle to the first mentioned plane, and a single element connected to the shaft and the blades substantially in a plane drawn at right angles to the axis of rotation of the shaft, for uniting the blades to the shaft.

9. A fan, including a shaft, a pair of convexo-concave blades diverging from a plane drawn through the axis of rotation of the shaft, a second pair of convexo-concave blades diverging from a plane drawn through the axis of rotation of the shaft at an angle to the first mentioned plane, and a spider extending in a plane at right angles to the shaft and connected thereto and to all of the blades.

10. A fan, including a plurality of convexo-concave blades radiating in different directions from the center of an imaginary sphere, said blades having their extreme edges shaped to coincide with the periphery of said sphere, a shaft intersecting the center of said sphere, and means for connecting said blades to said shaft.

11. A fan, including a shaft, a flat blade holder mounted on the shaft and including curved radiating arms provided with oppositely extending wings, each of which follows the curvature of its respective arm, and oppositely extending blades carried by the arms through said wings, each of said blades being curved in the direction of its height and in the direction of its width.

In testimony whereof I have hereunto affixed my signature.

SOCRATES A. XIPPAS.
